HANDLE FOR CULINARY IMPLEMENT

Casimir F. Gruska, Chicago, Ill., assignor to American Home Products Corporation, New York, N.Y., a corporation of Delaware

Filed Aug. 20, 1969, Ser. No. 18,779

Term of patent 14 years

Int. Cl. D8—02

U.S. Cl. D44—29

FIG. 1

FIG. 2

FIG. 3

FIG. 4

FIG. 5

FIG. 1 is a front elevational view of a handle for culinary implement showing my new design.

FIG. 2 is a side elevational view thereof.

FIG. 3 is an end elevational view thereof from the left of FIG. 2.

FIG. 4 is an end elevational view from the right of FIG. 2.

FIG. 5 is an enlarged fragmentary sectional view showing the grooves of FIGS. 1 and 2.

I claim:

The ornamental design for a handle for culinary implement, as shown.
